FUEL PUMPING AND SCAVENGING
MECHANISM

Paul Gordon Horstman, Ida Grove, Iowa

Application February 21, 1939, Serial No. 257,738

6 Claims. (Cl. 123—32)

This invention relates to new and useful improvements in fuel pumping and scavenging means especially adapted for two-cycle engines such as the present day Diesel engine.

The principal object of the present invention is to provide a simple and positive acting mechanism whereby fuel can be pumped at the required pressure to the cylinders of a multi-cylinder engine of the two-cycle type and controlled with a minimum amount of effort and attendance on the part of the operator.

Another important object of the invention is to provide a fuel pumping and scavenging assembly for two-cycle engines wherein the fuel injection, air admission and scavenging operations take place in a proportionate and precision-like manner.

Still another important object of the invention is to provide mechanism of the character stated which can be readily adjusted to a point where the operation will take place smoothly and with a minimum amount of wear on the parts involved.

These and other objects and advantages of the invention will become apparent to the reader of the following specification.

In the drawings:

Figure 1 represents a side elevational view of the improved engine.

Figure 2 is a fragmentary vertical sectional view on the line 2—2 of Fig. 1.

Figure 3 is a fragmentary longitudinal sectional view.

Figure 4 is an end elevational view of the mechanism.

Figure 5 is an inside elevational view of the fuel distributing and pumping head.

Figure 6 is a vertical sectional view through the fuel distributing and pumping head.

Figure 7 is a section substantially on the line 7—7 of Figure 6.

Figure 8 is a side elevational view of one of the check valves of the fuel distributing and pumping heads.

Figure 9 is a section on the line 9—9 of Figure 8.

Figure 10 is a fragmentary detailed sectional view through the head taken substantially on the line 10—10 of Figure 3.

Figure 11 is a perspective view of the valve element of the injector valve shown in Figure 13.

Figure 12 is a fragmentary plan view of one of the injector valves.

Figure 13 is a fragmentary sectional view longitudinally through one of the injector valves.

Figure 14 is a fragmentary detailed sectional view through the fluid pressure operating means for the pumps controlling shaft.

Figure 15 is a fragmentary elevational view showing the controlling arm for the pumps controlling shaft.

Referring to the drawings wherein like numerals designate like parts, it can be seen that numeral 5 generally refers to a two-cycle engine for the major part of conventional design. The engine involves a sectional head construction generally referred to by numeral 6, the same consisting of the upper semi-cylindrical shell section 7 and the lower semi-cylindrical shell section 8, which when secured together by machine screws 9 form the cylinder in which the sleeve 10 is rotatably mounted.

This sleeve 10 is constructed of a plurality of cylindrical sections 11, one for each of the cylinders 12 of the engine, these cylinder sections 11 being arranged in end to end relation and having end flanges bolted together as at 13 with suitable anti-frictional means 14 interposed between the ends thereof, or if desired this means 14 may be in the form of packing rings.

The engine being of the two-cycle type, each of the cylinder sections 11 carries a pair of diametrically located and oppositely directed fuel injectors 15—15 and furthermore at diametrically opposite points and substantially 90 degrees removed from each of the injectors 15 is an air opening 16. These air openings and injectors 16 and 15, respectively, are successively registerable with the port 17 of the corresponding cylinder 12.

As shown in Figure 2, numeral 18 represents the usual pre-heater found on two-cycle engines such as the Diesel type. Preheaters for starting engines of this character are of different types, some being electrically heated such as the one briefly illustrated, and others in the nature of plugs which are heated blood red by a blow torch or equivalent means.

At one end of the engine is the housing 19 having the air inlet 20 and in this housing is the fan 21 suitably driven from the crankshaft (not shown) for supplying air through the conduit 22 and through the head 23 to the interior of the sleeve 10. This air is supplied under pressure and obviously as the pistons 24 move downwardly and open up the exhaust port 25, the corresponding air admission port 16 will register with the cylinder port 17 so that a blast of air will sweep out or scavenge the cylinder, and upon the up-stroke of the piston sufficient air

will remain in the cylinder to combine with the fuel which will be subsequently injected.

At the opposite end of the engine is the fuel pumping and distributing head generally referred to by numeral 26, the same consisting of the cylindrical case 27 which is flanged as at 28 and apertured as at 29 to accommodate machine screws 30 for securing the ring gear 31 in place on the head.

A plate 32 is secured to the outside of the case 27 by machine screws 33 and this plate is formed with the centrally located opening 34 which is normally closed by the disk 35 which has packing means 36 interposed between itself and the outside of the plate 32.

The plate 35 is formed with a central opening for receiving the control shaft 37 and this disk 35 is keyed as at 38 to the shaft 37, and a nut 39 on the shaft with a collar 40 between itself and the disk 35 prevents displacement of the disk and serves to hold the disk snugly against the plate 32. A threaded nipple 41 extends from the shaft 37 and to this can be connected the fuel supply line 42 (see Figure 1). A duct 43 extends from the nipple 41 and opens through the bearing sleeve 44 at the inner end of the shaft 37 so that the fuel passes into the chamber 45 of the case 27 from where it is distributed from the pumps by way of the tubes 46 to the various injectors 15.

As shown in Figure 7, a plurality of cylinder structures 47 are disposed in radial relation with respect to the shaft 37, in the case 27 and in each of these cylinders 27 is operative a piston 48. The space 49 between the cylinders is in communication with the chamber 45 by means of the tubes 50 which extend from this chamber 45 and open into the said pocket 49.

The outer end of each of these cylinders 47 is constructed to form a chamber 51 which has a duct 52 extending therefrom to a corresponding nipple 53 on the inner side of the case 27 and to these nipples 53 connect the aforementioned distributing tubes 46.

A bushing 54 is threadedly engaged into one side of each of the pump cylinders 47 for slidably receiving a corresponding tubular valve stem or guide 55 which has its outer end flanged as at 56 while its opposite end or end within the chamber 51 is shaped to form a valve head 57 which is adapted to seat against the bushing as in the manner substantially shown in Figure 7 when there is no suction effect taking place thereon as the result of the inward movement of the corresponding plunger 48. These tubular stems 55 are formed with openings 58 adjacent their inner ends so that when the valve elements 57 are moved inwardly of their corresponding cylinders 47 the openings 58 will communicate the pocket 49 with the chambers 51.

As shown in Figure 7, surrounding the sleeve 44 is the ring 59 from which extend a plurality of ears 60 to which the connecting rods 61 of the pistons 48 are pivotally connected, and interposed between the ring 59 and the bearing sleeve 44 are the ball bearings 62.

However, should the shaft 37 be moved downwardly, and obviously when this is done the disk 35 moves downwardly on the plate 32, the shaft 37 will be eccentrically located with respect to the case 27 and obviously rotation of the case 27 will result in a reciprocation of the pistons in their cylinders 47 to perform the necessary pumping operation. The extent to which these pistons are actuated to control the speed of the engine is controlled and regulated by the extent of

movement of the shaft 37 to change the degree of eccentricity thereof. The means for changing the position of the shaft 37 to an eccentric position consists of a cylinder 63 in which a plunger 64 is operative. A manually controlled rod 65 is employed for operating the plunger 64 in the cylinder 63 against a volume of oil or other liquid, this being forced through the tube 66 to the bore 67 of the block 68 which is secured by an arm 69 to the crank case 70 of the engine. In the bore 67 is the follower piston 71 from which extends the rod 72, this rod extending upwardly, and as shown in Figure 15, has a ball head 73 which is seated in the socket 74 of the rocker 75, which is fulcrumed as at 76 on the bracket 77.

The rocker 75 merges with the aforementioned collar 40 which is keyed by the same key 38 to the shaft 37. Obviously when the piston 71 (see Figure 14) is lifted under fluid pressure, the arm 75 will be rocked so that the shaft 37 will be lowered so as to eccentrically place the shaft 37 and as before stated the extent of movement of the shaft 37 below the center of the case 27 will determine the extent of movement of the pistons 48 and the amount of fuel which will be sucked into the chambers 51 and then forced through the tubes 46 to the injectors 15.

The means for rotating the head structure 26 consists of the aforementioned ring gear 31 and the pinion 18, the latter being on the shaft 79 which has a suitable drive take-off from the crankshaft (not shown).

Each of the injectors consists of a barrel 80 having one end threadedly engaged as at 81 into a boss 82 in the sleeve 10 and each of these bosses 82 is bored as at 83 and counterbored to receive a bushing 84 which serves as a valve seat. Extending from the counterbore is the Venturi opening 85 communicating the interior of the shell 80 with the cylinder port 17 when registration takes place. In each of the shells 80 is a follower 86 carrying the needle valve 87 which is cooperative with the seat bushing 84. A second follower in the form of a plate 88 is operative in the shell 80 and can be adjusted by the set screw 89 and between this follower 88 and the follower 86 is the compression spring 90. Obviously, when sufficient pressure of the fuel in the tubes 46 occurs, the follower 86 is lifted to displace the needle valve 87 so that injection of the fuel into the corresponding cylinder 12 takes place.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In a two-cycle engine, cylinders each having a port for the admission of air and fuel, a rotatable sleeve common to all of the cylinders, said sleeve being provided with fuel injectors for injecting fuel into the cylinders through the said ports, said sleeve being provided with a port for scavenging and air admissions in each of the cylinders registerable with the port of the corresponding cylinder, and force means for forcing air through the sleeve and through the ports of the cylinders when the ports of the sleeve communicate the sleeve with the ports of the cylinders.

2. In a two-cycle engine, cylinders each having a port for the admission of air and fuel, a rotat-

able sleeve common to all of the cylinders, said sleeve being provided with fuel injectors for injecting fuel into the cylinders through said ports, said sleeve being provided with a port for scavenging and air admission in each of the cylinders registrable with the port of the corresponding cylinder, and force means for forcing air through the sleeve and through the ports of the cylinders when the ports of the sleeve communicate the sleeve with the ports of the cylinders and a pumping and distributing mechanism on one end of the sleeve for the injectors.

3. In a two-cycle engine, cylinders each having a port for the admission of air and fuel, a rotatable sleeve common to all of the cylinders, said sleeve being provided with fuel injectors for injecting fuel into the cylinders through said ports, said sleeve being provided with a port for scavenging and air admission in each of the cylinders registrable with the port of the corresponding cylinder, and force means for forcing air through the sleeve and through the ports of the cylinders when the ports of the sleeve communicate the sleeve with the ports of the cylinders and a pumping and distributing mechanism on one end of the sleeve for the injectors, said mechanism having a plurality of radially disposed pump cylinders therein, a piston in each of the pump cylinders, a conduit for each of the pump cylinders to a corresponding injector, said mechanism constituting a reservoir for oil, each of the pump cylinders being provided with a check valve through which fuel from the reservoir can be drawn.

4. In a two-cycle engine, cylinders each having a port for the admission of air and fuel, a rotatable sleeve common to all of the cylinders, said sleeve being provided with fuel injectors for injecting fuel into the cylinders through said ports, said sleeve being provided with a port for scavenging and air admission in each of the cylinders registrable with the port of the corresponding cylinder, and force means for forcing air through the sleeve and through the ports of the cylinders when the ports of the sleeve communicate the sleeve with the ports of the cylinders and a pumping and distributing mechanism

having a plurality of radially disposed pump cylinders therein, a piston in each of the pump cylinders, a conduit for each of the pump cylinders to a corresponding injector, said mechanism constituting a reservoir for oil, each of the pump cylinders being provided with a check valve through which fuel from the reservoir can be drawn, said mechanism being provided with a short centrally located shaft, connections between the pistons operative in the pump cylinders and the shaft and means for adjusting the shaft diametrically with respect to the reservoir.

5. In a two-cycle engine, cylinders each having a port for the admission of air and fuel, a rotatable sleeve common to all of the cylinders, said sleeve being provided with fuel injectors for injecting fuel into the cylinders through said ports, said sleeve being provided with a port for scavenging and air admission in each of the cylinders registrable with the port of the corresponding cylinder, and force means for forcing air through the sleeve and through the ports of the cylinders when the ports of the sleeve communicate the sleeve with the ports of the cylinders and a pumping and distributing mechanism on one end of the sleeve for the injectors, said mechanism including an eccentrically adjustable shaft.

6. In a two-cycle engine, cylinders each having a port for the admission of air and fuel, a rotatable sleeve common to all of the cylinders, said sleeve being provided with fuel injectors for injecting fuel into the cylinders through said ports, said sleeve being provided with a port for scavenging and air admission in each of the cylinders registrable with the port of the corresponding cylinder, and force means for forcing air through the sleeve and through the ports of the cylinders when the ports of the sleeve communicate the sleeve with the ports of the cylinders and a pumping and distributing mechanism on one end of the sleeve for the injectors, said mechanism including an eccentrically adjustable shaft, and manual means for adjusting the said shaft.

PAUL GORDON HORSTMAN.
